(57) **CLAIM**

The ornamental design for a tamper proof cork system, as shown and described.

DESCRIPTION

FIG. 1 is a side view of a first embodiment of a tamper proof cork system, showing my new design;
FIG. 2 is a perspective cross sectional view of the tamper proof cork system of FIG. 1, taken in the direction of line 2-2 on FIG. 1;
FIG. 3 is a top view of the tamper proof cork system of FIG. 1;
FIG. 4 is a bottom view of the tamper proof cork system of FIG. 1;
FIG. 5 is a side view of the tamper proof cork system of FIG. 1 in which a detachable portion of the tamper proof cork system has been partially removed;
FIG. 6 is a side view of the tamper proof cork system of FIG. 5 in which the detachable portion of the tamper proof cork system has been completely removed;
FIG. 7 is a bottom view of the tamper proof cork system of FIG. 6;
FIG. 8 is a side view of the tamper proof cork system of FIG. 1 coupled to a bottle;
FIG. 9 is a perspective cross sectional view of the tamper proof cork system of FIG. 8, taken in the direction of line 9-9 on FIG. 8;
FIG. 10 is a side view of the tamper proof cork system of FIG. 6 coupled to a bottle;
FIG. 11 is a side view of a second embodiment of a tamper proof cork system, showing my new design;
FIG. 12 is a perspective cross sectional view of the tamper proof cork system of FIG. 11, taken in the direction of line 12-12 on FIG. 11;
FIG. 13 is a top view of the tamper proof cork system of FIG. 11;
FIG. 14 is a bottom view of the tamper proof cork system of FIG. 11;
FIG. 15 is a side view of the tamper proof cork system of FIG. 11 in which a detachable portion of the tamper proof cork system has been partially removed;

(Continued)

FIG. 16 is a side view of the tamper proof cork system of FIG. 15 in which the detachable portion of the tamper proof cork system has been completely removed;
 FIG. 17 is a bottom view of the tamper proof cork system of FIG. 16;
 FIG. 18 is a side view of the tamper proof cork system of FIG. 11 coupled to a bottle;
 FIG. 19 is a perspective cross sectional view of the tamper proof cork system of FIG. 18, taken in the direction of line 19-19 on FIG. 18; and,
 FIG. 20 is a side view of the tamper proof cork system of FIG. 16 coupled to a bottle.
 The evenly broken lines are shown for the purpose of illustrating cross hatching applied to cut surfaces that form no part of the claim. The dot-dot-dash lines represent environmental subject matter. None of the broken lines are part of the claimed design.
